CLAIM

The ornamental design for an athletic shoe with wrap-around pocket, as shown and described.

DESCRIPTION

FIG. 1 is a right side elevational view of an athletic shoe with wraparound pocket showing my new design;
FIG. 2 is a left side elevational view thereof;
FIG. 3 is a top plan view thereof;
FIG. 4 is a bottom plan view thereof;
FIG. 5 is a rear elevational view thereof;
FIG. 6 is a front elevational view thereof;
FIG. 7 is a right side elevational view of another embodiment of my new design of FIGS. 1-6, the left side being a mirror image thereof;
FIG. 8 is a top plan view of FIG. 7, the bottom plan view being identical to FIG. 4;
FIG. 9 is a front elevational view of FIG. 7, the rear view being identical to FIG. 5.
